(57) **CLAIM**

The ornamental design for a motorcycle floorboard cover, as shown and described.

DESCRIPTION

FIG. 1 is a perspective view of the motorcycle floorboard cover of the present invention.

FIG. 2 is an elevational view of the side of the motorcycle floorboard cover not shown in FIG. 1.

FIG. 3 is an elevational view of the side of the motorcycle floorboard cover shown in FIG. 1.

FIG. 4 is an elevational view of the end of the motorcycle floorboard cover not shown in FIG. 1.

FIG. 5 is an elevational view of the end of the motorcycle floorboard cover shown in FIG. 1.

FIG. 6 is a top plan view of the motorcycle floorboard cover of FIG. 1; and,

FIG. 7 is a bottom plan view of the motorcycle floorboard cover of FIG. 1.

The broken lines in the Figures are for illustrative purposes only and form no part of the present invention.
